UNITED STATES PATENT OFFICE.

WILLIAM ROCHE, OF JERSEY CITY, NEW JERSEY.

DESIGN FOR AN ELECTRIC-LAMP HOLDER.

SPECIFICATION forming part of Design No. 33,036, dated July 31, 1900.

Application filed June 27, 1900. Serial No. 21,853. Term of patent 7 years.

To all whom it may concern:

Be it known that I, WILLIAM ROCHE, a citizen of the United States, and a resident of Jersey City, in the county of Hudson and State of New Jersey, have invented and produced a new and original Design for an Electric-Lamp Holder, of which the following is a full, clear, and exact description.

Reference is to be had to the accompanying drawing, forming a part of this specification, which drawing is a perspective view of an electric-lamp holder embodying my design.

The leading feature of my design consists in an electric-lamp holder having a cup-shaped body with a shank or pin extending from the center thereof at the rear, and a forwardly-convexed front plate.

As shown in the drawing, the cup A is curved about spherically, and from the cen-

ter of the cup, at the rear thereof, extends 20 tangentially downward the shank or pin B, terminating in a point B'. At the circular front edge of the cup A is located the forwardly-convexed front plate C, on which appears a picture.

Having thus described my invention, I claim as new and desire to secure by Letters Patent—

The design for an electric-lamp holder as herein shown and described.

In testimony whereof I have signed my name to this specification in the presence of two subscribing witnesses.

WILLIAM ROCHE.

Witnesses:

JOHN LOTKA,
EVERARD BOLTON MARSHALL.
